United States Patent Office

Des. 193,139
Patented July 3, 1962

193,139

OZONE GENERATOR

Julian H. Karp, Los Angeles, Calif., assignor to Electro-
gen Industries, Inc., Los Angeles, Calif., a corporation

Filed Apr. 5, 1961, Ser. No. 64,629

Term of patent 3½ years

(Cl. D16—2)

FIGURE 1 is a front perspective view of an ozone generator, showing my new design;

FIGURE 2 is a rear elevation thereof;

FIGURE 3 is a top plan view thereof;

FIGURE 4 is a side elevation taken from the side opposite that shown in FIGURE 1; and

FIGURE 5 is a bottom plan view thereof.

I claim:

The ornamental design for an ozone generator, as shown.
